PROCESS FOR PRODUCING A REPLICA
OF A SURFACEEugene S. Machlin, Cleveland Heights, and
Louis L. Ornstein, East Cleveland, Ohio

Application May 15, 1945, Serial No. 593,897

2 Claims. (Cl. 35—50)

(Granted under the act of March 3, 1883, as
amended April 30, 1928; 370 O. G. 757)

1

The invention pertains to the replica or reproduction of the characteristics of a surface on a non-metallic film, said non-metallic replica film being preserved for examination, and to the process of producing and using the replica film.

Many items have been made in the past to obtain a measure of the surface finish of machine finished surfaces. Such methods have made use of expensive instruments which are not available for wide distribution because of their high cost. Other less expensive methods have been used to reproduce surfaces of specimens in the field of scientific research. These latter methods make use of replicas of the surfaces which are to be reproduced.

It is an object of this invention to make use of the replica type of reproduction process in a unique fashion which enables very quick determinations of the character or surface finish of a surface to be obtained.

A further object of this invention is to provide a method for obtaining the surface finish or measure of surface character of internal surfaces. For example, where a measure of the area of indentation of a surface is desired, ordinary tracer-type surface finish measuring instruments will not measure this area. However, the use of the replica reproduction process in conjunction with a standard comparison according to the present invention will enable these areas of indentation to be measured. Machines now available for measuring internal indentation areas are very costly and hence limited in use. The replica reproduction process according to the present invention offers an inexpensive, easy method of obtaining internal indentation area measurements.

A further object is to provide an inspection surface finish control by means of, for example, replica reproduction comparison measurements or other measurements.

Other objects and features of the invention will be apparent from the following description taken in conjunction with the accompanying drawings which are exemplary and in which:

Fig. 1 is an exploded view of the elements of the article and showing the elements employed in the process of producing the replica.

Fig. 1a is a view of the prepared replica blank and its backing.

Fig. 2 is a view showing the parts in place after the solvent has been applied and ready for the application of pressure.

Fig. 3 is a view of the completed replica with its backings.

Fig. 4 is a plan view of the same.
Fig. 5 is a view of a comparison apparatus.
The surface replica and process of the present invention has been found particularly advantageous for measuring the porosity of chromium plated surfaces, while not being limited thereto.

One of the most promising cylinder-bearing surfaces for piston rings operating in an aircraft engine at high power outputs is porous chromium plate. The chief difficulty in the use of chromium plating has been that some porous chromium-plated cylinders wore exceptionally well whereas others wore exceptionally poorly. Because of the uncertainty of the results chromium plating has not been generally adopted for cylinders of high-power engines. The reason for the difference in operation between two cylinders that are chromium plated by the same method may lie in the type and degree of porosity.

10 The lack of adequate methods of inspecting and specifying the optimum porosity of chromium-plated surfaces has greatly retarded progress in the use of porous chromium plate. For this reason a satisfactory method of measuring 15 the porosity of porous chromium-plated surfaces has been sought. Such instruments as the Brush surface analyzer, the Profilometer, and a light-reflection meter have been used with little success.

20 The process of the present invention is simple, fast and sufficiently accurate to specify porosity of chromium-plated cylinders for aircraft engine tests. It is particularly suited for shop use as a means of inspection prior to engine operation.

25 30 The blank 1 for the replica may desirably be prepared by brushing, spraying, dipping, pouring or otherwise applying a liquid non-metallic substance such as stripping lacquer or plastic material in a thin film on a smooth, preferably 35 very highly polished surface, the roughness of 40 which is less than 3 microinches, R. M. S. After the film has dried on the smooth surface, it is stripped or peeled therefrom, and may be cut into strips or pieces of the desired size. Other

45 methods may be used to prepare the blank film 1, such as rolling a plastic or lacquer film or pressing said film, so long as the surfaces of the film are not marred by the surfaces of the rolls or press.

50 In the embodiment shown in the drawing, 1 represents the nonmetallic prepared film; 2 is the surface which is being reproduced; 3 is the solvent applied in any suitable way which is either placed on 2 or on the under side 4 of 1; 55 5 is a backing for 1 having an adhesive layer

on its under side 6. There is an opening 7 in the backing 5 through which pressure is applied by means of pad 8 which preferably is not soluble in solvent 3.

The film 1 may desirably be provided with the backing 5 of suitable material, such as paper or cardboard or other flexible material, having an opening therein, desirably such as indicated at 7. The backing 5 is preferably provided on its side 6 with adhesive by means of which the side 6 of backing 5 is secured to the blank film 1, as indicated in Fig. 1a. A supply of blanks for replicas may be prepared and stored for future use, if desired.

In obtaining a replica reproduction of the surface 2, solvent 3 for the film 1 is applied by spraying or otherwise, either on the surface 2 or on the side 4 of film 1. A thin film of solvent is desirable. Immediately, or a few seconds after the solvent has been applied, the side 4 of the film 1 is pressed into intimate contact with the surface 2 desirably by hand pressure applied against the protecting pad 8, and through the opening 7 in backing 5. Fig. 2 shows the parts in place after the solvent has been applied, ready for pressure to be applied to the pad 8. Pressure is maintained for a short time, preferably not less than 15 seconds and not more than 1 minute. During the maintenance of pressure the film becomes dried in contact with the surface to be reproduced.

After the pressure and drying interval has been completed, the replica film 1 is gently peeled or stripped from the surface 2. It is then provided with a suitable mounting or backing means which may desirably comprise a backing such as indicated at 10 having an adhesive side 9 to be attached to the replica film with the opening 11 in the backing 10 matching or registering with the opening 7 of the backing 5. This is shown in Figs. 3 and 4, in which 1 is the non-metallic replica film; 5 and 10 are the preferably flexible backings for the film 1; 6 and 9 are the adhesive sides of the backings 5 and 10; and 7 and 11 represent the openings in the backings 5 and 10.

The replica, as seen in Figs. 3 and 4, is then ready for viewing and examination, for example, by a standard comparison method or other surface finish measurements.

In order to measure porosity or examine the replica film; a magnified image of the replica may desirably be projected onto the screen of a film viewer, such as a 35 millimeter film viewer, as indicated in Fig. 5.

In Fig. 5, the film viewer or projection apparatus is indicated at 12. A strip, desirably consisting of a number of standard replicas of known porosities or surface configuration, sandwiched between two strips of celluloid is mounted in place in the film viewer or projection apparatus 12, as indicated at 13. The standard or known replicas preferably have been accurately calibrated for percentage porosity by measuring the area of the pores. A strip in which is placed the sample replica whose surface finish or surface character is being compared to standard replica strip 13, is indicated at 14.

The projections of the standard and unknown porosity surface replicas are indicated at 15 and 16, respectively. To obtain a comparison, the sample unknown replica 14 is placed in the projection or viewing apparatus 12, so that its projection appears at 16 next to the projection of the standard replica 13 which appears at 15. Any known replica image can be quickly obtained by shifting the standard replica strip. The un-

known porosity is obtained by matching the sample replica image to one of the known replica images.

The comparison method enables an untrained operator, to choose or bracket the limits of the unknown porosity or the percentage area of surface indentation to nominal surface area, to within approximately 5 percent of the area of surface indentation of the sample replica.

An important feature of the method of the present invention is the action of the solvent 3 to soften the side 4 of film 1 so that the film 1 being placed in intimate contact with surface 2, the softened side 4 will conform to the asperities and hollows existing in the surface 2. Such conformity will become permanent as the softened side 4 of film 1 hardens and sets. Such an action and method provides for a very quick measurement of surface finish or surface indentation area to be obtained.

The surface porosity of a chromium-plated cylinder can be identified by the process of the present invention as to type and measured as to value in approximately one minute.

The replica method is suitable for use in machine shops and plating plants where a quick check of the type or the quality of the porosity of chromium-plating or other surfaces is required. The apparatus is simple and inexpensive.

Inexperienced personnel can be trained to measure porosity in a relatively short time. Approximately two minutes are required for a complete measurement, the first minute being required to make the replica and the second minute to match the unknown porosity.

As a film material, it has been found that Ault and Wiborg Protektol No. 28 is particularly suitable. This material is easily stripped from the highly polished surface in forming the replica

blank without marring the surfaces of the film in any way.

Materials other than the stripping lacquer or liquid plastic may be used in this method, with suitable solvents therefor.

A suitable solvent for the Protektol No. 28 is Ault and Wiborg No. 2069, Protektol Reducer.

If this method were used in a honing shop, removal of the cylinder from the honing machine would be unnecessary. The surface to be checked, may be cleaned, the replica taken, the porosity measured, and honing continued or stopped, depending upon what results showed.

Any standard film viewer that is inexpensive or readily portable may be used in the process, and should preferably be installed in a darkened room. It may be desirable to have the film of known replicas wound on a spool so that the known samples can be moved across the field of view with a minimum of difficulty. The viewer may preferably be provided with reversible motor driven shafts. Both samples are subjected in the viewer to the same lighting conditions and are shown side by side to facilitate comparison. A magnification of 16 may desirably be employed.

Magnifications as high as 50, however, are available with stock equipment. Lower magnification has the advantage that a larger area can be examined and a more representative sample of porosity can thus be obtained. Samples of both channeled and normal types of porosity have been examined and are readily distinguishable. Thus, type of porosity as well as percentage porosity can be obtained by this method.

It will be understood that various changes in the construction and arrangement of parts and in

the process may be made without departing from the spirit of the invention and it is not intended to limit the invention other than by the terms of the appended claims.

The invention described herein may be manufactured and used by or for the Government of the United States of America for governmental purposes without the payment of any royalties thereon or therefor.

What is claimed is:

1. Steps in a method of obtaining a replica or reproduction of a surface comprising applying a backing having an opening therein to a strip of non-metallic film by means of adhesive to act as a protection against damage and for ease in handling, applying the unbacked side of said film to a surface, the features of which it is desired to reproduce, with the application of liquid solvent for said film, applying pressure to a localized portion of said film through said opening in the backing, allowing the film to dry in pressure contact with said surface, removing the film from said surface, adhesively applying a protecting backing having an opening therein to the unbacked side of said film with the opening substantially registering with the opening in the backing first mentioned, and exposing the replica on the said localized portion of the film which is formed in that part of the film bounded by the edges of the openings in the backings.

2. Steps in a method of obtaining a replica or reproduction of a surface comprising applying a backing having an opening therein to a strip of non-metallic film by means of adhesive to act as a protection against damage and for ease in handling, applying the unbacked side of said film to a surface, the features of which it is desired to reproduce, with the application of liquid solvent for said film, applying a protecting pad to said backing overlying the opening therein, applying pressure to a localized portion of said film through said opening in the backing by pressing on said protecting pad, allowing the film to dry in pressure contact with said surface, removing the film from said surface, adhesively applying a protecting backing having an opening therein

to the unbacked side of said film with the opening substantially registering with the opening in the backing first mentioned and thereby exposing the replica on the said localized portion of the film which is formed in that part of the film bounded by the edges of the openings in the backings.

EUGENE S. MACHLIN.
